UNITED STATES PATENT OFFICE.

FRANK C. LEETHEM, OF MIDDLETOWN, NEW YORK, ASSIGNOR TO LATHAM AUTOMATIC REGISTERING COMPANY, A CORPORATION OF ILLINOIS.

IMPOSING-TABLE AND PROOF-PRESS.

1,139,984.

Specification of Letters Patent. Patented May 18, 1915.

Application filed March 20, 1912, Serial No. 685,047. Renewed April 8, 1915. Serial No. 20,339.

To all whom it may concern:

Be it known that I, FRANK C. LEETHEM, a citizen of the United States, and resident of Middletown, in the county of Orange and 5 State of New York, have invented certain new and useful Improvements in Imposing-Tables and Proof-Presses, of which the following is a specification.

This invention relates to the art of making up printers' forms and is particularly useful where printing is to be done in two or more colors.

One of the objects of the invention is to produce a machine which will facilitate the 15 accurate placing of the printing plates in the chase when the form is being made up.

One of the principal objects of the invention is to provide a construction which will enable plates, type or printing sheets, or 20 forms, to be accurately imposed or alined with respect to a longitudinal and transverse axis; and the machine is constructed in such a way that the position of the plates in the form may be positively determined either from the face measure or the 25 extreme edge of the bevel. By making up the forms corresponding to the different colors in this way, a substantially perfect register may be secured.

30 A further object of the invention is to provide the machine with means for taking off a proof sheet in order to compare the register of two or more different forms which are being made up simultaneously on 35 different machines. Where only one machine is in use, however, the proof sheet will then be taken off simply for the ordinary purposes.

Further objects of the invention will appear from a thorough understanding of the 40 invention.

In carrying out the invention, the machine preferably comprises a table upon which the form is made up. The table is 45 provided with means, such as an alining head or bar, for alining the chase, and is also provided with a movable transverse gage which travels longitudinally on the table and alines the plates or other printing matter, within the chase in one direction. 50 Moving on this transverse gage which is the

main gage, other gages are provided which aline the plates or forms in a direction at right angles to the main gage. Scales are provided so that the position of the plates 55 may be predetermined with great accuracy.

The combination of gages is very useful in a case where a number of plates or forms of the same size are to be placed at different positions in the bed, that is, where an arrangement of the plates or forms is a regular one.

One of the objects of the invention is to facilitate the placing of a plurality of plates or forms in regular order throughout a form. 60

The invention consists in the general combination of parts and simplicity of details hereinafter described, all of which contribute to produce an efficient imposing table.

A preferred embodiment of my invention 70 will be particularly described in the following specification, while the broad scope of my invention will be pointed out in the appended claims.

In the drawings, which fully illustrate my 75 invention, Figure 1 is a plan of the complete machine, showing a form being made up upon the table and illustrating the manner in which the gages coöperate to aline the plates or forms. Fig. 2 is a side elevation of the table, the supporting legs being broken away. This view also shows a portion of the drum of the proof cylinder 80 broken away to illustrate the manner in which the proof sheet is held thereupon.

Fig. 3 is a plan showing a part of the table and illustrating special means for taking a proof sheet from plates which have been set up in the form. This arrangement involves the use of a transverse clamp which may 85 be supported by the bars of the cross gages. Fig. 4 is a front elevation broken away, and illustrates the manner in which the clamping bar for the proof sheet is constructed, and also showing the manner in 90 which it is supported on the gage bars.

Fig. 5 is a front elevation showing the forward side of the carriage which supports the main gage and also showing the arrangement for mounting and adjusting the cross gages. This view also shows the means for advancing the carriage along the table. 100

Fig. 6 is a vertical section taken through the carriage longitudinally with the table, and illustrating the main gage and the means for adjusting it and operating it. 5 Fig. 7 is a rear view of the parts shown in Fig. 6 and illustrating means for regulating the descent of a main gage plate. Fig. 8 is a plan showing a portion of the table and illustrating the manner in which the machine may be employed to locate the corresponding plates at different points on the table. Fig. 9 is a front elevation upon a larger scale showing one of the cross gages in detail, and also illustrating the means for 10 supporting a templet sheet upon the gages, to be used in locating a number of plates on the table as illustrated in Fig. 8. Fig. 10 is a vertical section through the edge of the table, illustrating the construction of a stop, 15 two of which are used in connection with the carriage to limit or adjust its movements along the table. Fig. 11 is a side elevation of a pin, a number of which are used on the table to facilitate the clamping of the chase 20 in position.

Referring more particularly to the parts and especially to Figs. 1 to 6, the machine comprises a large, horizontal table 1, which is supported on legs 2 at a suitable elevation 25 above the floor. One of the longitudinal edges of the table is formed with an upwardly projecting guide head or bolster 3 so that the upper face 4 of the table is slightly depressed, forming a shoulder 5 at 30 the side of the guide head 3, as indicated in Fig. 5. On the under side of the table 1, and near the longitudinal edges thereof I provide longitudinally disposed racks 6 which are held in place by small clip plates 40 7, received in notches formed in the sides of the racks as indicated in Fig. 5. Mounted to move longitudinally on the table, I provide a carriage 8, said carriage comprising housings 9 and 10 which are disposed 45 opposite each other and connected by a cross bar 11, as indicated in Fig. 6. Above the cross bar 11 the housings are connected by a scale bar 12, the upper edge of which is provided with a scale 13 as indicated. In 50 order to move the carriage along the table, I provide a cross shaft 14, the ends of which are mounted in the housings, and this shaft is provided with pinions 16 which mesh with the racks. Outside of the housings, 55 the shaft is provided with hand wheels 17, having offset handles 18 for rotating the wheels. The inner edges of these hand wheels are provided with scales 19, and each housing is provided with a pointer 20 in the 60 form of a short bar projecting out horizontally at the upper edge of each wheel. This pointer coöperating with the scale, indicates the amount of advance the carriage would have for a given rotation of the wheel.

As indicated in Fig. 6, near the cross bar 65 11, I provide a main gage bar 21 which is supported pivotally on the housings 9 and 10 by means of bent arms 22, said bent arms being attached on pivot studs 22a. The forward side of this gage bar 21 is provided 70 with a gage plate 23, the lower edge of which normally lies near the upper face of the form, and may descend upon it. In order to move the gage relatively to the carriage to force the gage plate 23 down onto 75 the face of the form when desired, the bent arms 22 are provided with rigid handles 24. In order to support the gage plate 23 resiliently, the gage bar 21 is provided with an upwardly extending inclined arm 25, the 80 end of which is provided with double forks 26 which support gudgeons 27 which project laterally from a sleeve 28. This sleeve forms a guide for a sliding stem 29, the forward end of which is pivotally attached at 85 30 to the rear side of the scale bar 12. Around the stem 29 a spring 31 is provided, which thrusts against the sleeve. Evidently, if the gage 23 is forced downwardly and released, the spring 31 will extend itself and 90 return the sleeve 28 to its normal position, thereby returning the gage. The extremity of the stem 29 is provided with a split pin 32, which limits the rearward movement of the sleeve.

In order to regulate the descending movement of the gage plate 23, the arm 25 is provided with an adjusting screw 33, the end of which lies near the rear face of the scale bar. Evidently by adjusting this screw the 100 scale bar will arrest the movement of the gage plate 23 at any point desired. On account of the arrangement at the forks 26, it will be evident that the stem 29 may be raised so as to disengage the gudgeons 27 105 from the forks and the gage bar 21 will then not be under the influence of the spring, and the gage plate 23 will descend by gravity on the table. This arrangement constitutes a "cast-off" device to relieve the gage 110 plate from the spring action. In order to enable the gage plate 23 to be normally held slightly elevated, but so that it can be let down when desired, I provide a movable button 34 on the rear side of the scale bar 115 as indicated in Fig. 7. This button normally permits only a partial descent of the gage bar. This button is in the form of an arm which swings on the fixed pivot 35. A stop pin 36 on the back of the scale bar normally supports this button with its enlarged end 37 directly adjacent the end of the adjusting screw 33. By moving the button 34 over against a second stop pin 38 it will be evident that the gage may have a complete 120 descent.

Attached on the forward side of the cross bar 11 I provide a cross slide 39. On this

cross slide 39 I provide a pair of cross gages having shoes 40 and 41 slipping freely on the slide. These shoes are identical in construction except that one is right, and the other, left hand. And all the parts associated with these shoes are likewise similar. One of these shoes is illustrated in detail in Fig. 5. These shoes are intended to slide onto the ends of the slide 39.

- 10 The upper portion of each shoe is provided with an upwardly extending forwardly inclined clamping head 42, and these clamping heads are provided with horizontal transverse openings which receive a horizontal connecting rod 43. This connecting rod enables the two shoes to be clamped together so as to slide as one piece along the side. For this purpose the clamping heads 42 are provided with clamping screws 44 as shown. Near the clamping heads 42 the shoes are provided with bosses 45, presenting vertical end faces 46 on the outer side, adapted to come against adjusting screws 47 mounted horizontally in the upper ends 25 of adjusting clamps 48 and 49. Each of these adjusting clamps or blocks slides freely on the slide unless clamped at any position desired by the clamping screw 50. The adjusting screws 47 have graduated 30 heads 51, coöperating with pointers 52 carried by the clamps for indicating the amount of advance which the shoes 40 and 41 will have for a given rotation of the corresponding adjusting screw. These screws 35 can be set as stops to limit the movement of the gages to a point slightly beyond the desired location, and may then be rotated slightly to adjust the gages exactly to the proper point. Each of the shoes 40 and 41 40 is provided with a pointer 53 which is offset inwardly and extends upwardly to co-operate with the aforesaid scale 13. The forward or reading edges of these pointers are in exact alinement with the lower edges 45 of cross gage plates 54 which extend longitudinally with the table. The arrangement for mounting and adjusting these cross gage plates 54 will now be described.

The forward sides of the gage shoes 40 50 and 41 are provided with outwardly projecting horizontal gage bars 55, and on each of these gage bars a pair of cross gages 56 is mounted. The cross gages 56 are attached to the bars 55 by means of clamping 55 screws 57, and comprise brackets or hangers 58 which may slide along the gage bars. The brackets are held against turning on the gage bars by pins 59 which run in slots 60 in the upper sides of the bars. Each bracket 58 is provided with a bifurcated foot 61 between the forks of which a gage holder 62 is pivotally mounted on a pin 63. These gage holders 62 project transversely of the table, and are provided with adjust-

ing screws 64 coöperating with the projecting toes 65 of the brackets 58, to enable the gage holders to be adjusted to the face of the form. These gage holders carry the aforesaid gage plates 54 in suitable sockets 66, as indicated in Fig. 9.

The upper sides of the gage holders 62 are provided with upwardly extending posts 67, the purpose of which will appear hereinafter, and these posts project upwardly from horizontal seats 68 below which each 75 gage holder is provided with a transverse opening 69. The openings 69 enable attachments to be made to the gage holders when desired.

As indicated in Figs. 1 and 5, the posts 80 67 which are outermost on the gage bars 55 may be provided with clamps 70 for the purpose of attaching gage stems 71. These gage stems may be clamped in any position by a clamping screw 72, and have downwardly curved points 73 which are adapted to descend to the face of the printing plate when desired. These gage stems or pointers 71 are used only in locating plates which have center marks somewhere on their surfaces and which are not alined by means of the gage plates 54.

In order to limit the movement of the carriage 8, and adjustably move the carriage and the gages carried thereby along 95 the table, the guide head 3 is provided with a pair of clamp stops 74 and 75, one of which is illustrated in detail in Fig. 10. The stop 74 which is near the inner end of the table in Fig. 1, has an adjusting screw 100 76 which projects toward the carriage, and this adjusting screw 76 has a graduated head 77 coöperating with the pointer 78 to indicate the amount of movement the carriage will be given for a certain rotation 105 of the adjusting screw. A similar adjusting screw 79 is mounted in the clamp stop 75, and its point also projects toward the carriage. It is similarly provided with a graduated head 80, coöperating with the 110 pointer 81, and it is further provided with a bent pointer 82, the body of which lies on the upper face of the guide head, so as to co-operate with the longitudinal scale 83 which is countersunk in the inner edge of the 115 guide head 3, as shown in Figs. 1 and 5. The clamping stops 74 and 75 are provided with shoes 84^a, which run in a dove-tail slot 84 in the edge of the table, and may be clamped in any desired position by clamping knobs or hand wheels 85, having threaded stems 86 engaging the shoes as illustrated in Fig. 10. A plurality of other shoes 84^b are provided in the slot 84 which are of the same construction as the shoes 84^a. All of 120 these shoes have shallow longitudinal slots 84^c to receive a corresponding tongue 84^d on the clamps to hold the clamps alined. This

arrangement enables me to use extra stops when desired, and the intermediate stops may be unscrewed and removed at will, to permit the carriage to pass their point of location on the table. As the shoes do not project beyond the table edge, the housing 9 of course is unobstructed by the intermediate shoes it may pass in its movement.

The housing 9 is provided on its sides with 10 stops 87 and 88 which coöperate respectively with the adjusting screws 76 and 79. The pointer 82 extends along the table so that the reading edge 89, when the end of the adjusting screw 79 is against the stop 88, will 15 lie substantially in alinement with the lower edge of the gage plate 23; and when the zero of the graduated head 80 is under the pointer of the stop 75, an exact alinement between the edge 89 and the gage plate 23 may 20 occur.

In using the machine to impose plates in the form, a chase 90 is placed on the upper surface of the table with one end abutting against the shoulder 5 of the alining head. 25 The chase employed is of the same thickness as the depth of the shoulder 5, so that when in this position, the upper face of the chase is flush with the upper face of the guide head 3. This chase is then clamped rigidly 30 in position by means of furniture 91 of the form shown, the outer pieces of the furniture being pressed against pins 92, one of which is shown in detail in Fig. 11. These pins have square heads 93 and round shanks 94, which are adapted to be received in any one of a plurality of round sockets 95 which are formed in the table near the ends and the outer longitudinal edge. The rails of the chase are provided with locks 40 96 for clamping the chase against the furniture. The interior of the chase 90 may be filled with square bases 97, which are preferably cut to dimension on some well known type system, such as the pica system. In alining 45 two plates, such as the plates 98 and 99, the outside dimensions of the plates being known, it is only necessary to adjust the cross gages 56 to the proper distance apart to allow for the desired margin between the 50 plates. In order to do this, one of the clamping screws 44 at least, must be loosened, so as to permit the gage shoes 40 and 41 to approach or recede from each other. The reading on the scale 13 by means of the 55 pointers 53 indicates the distance between gages, and when the gages have been set to the proper position they are clamped rigidly together by means of the clamping screws 44 and the connecting rod 43. The gage shoe 40 is then slid to approximately the proper position to locate the edge of the plate 99, but in doing so, the reading on the scale should be a little less than that desired when the plate is completely alined. Having brought 60 the shoe to this position, the corresponding

adjusting clamp 48 is slid up to the shoe 40 until the point of the screw 47 comes against the stop 45. The clamp 48 is then rigidly secured to the slide by the clamping screw 50 and the adjusting screw 47 is then rotated so as to advance the shoe 40 slowly along the slide. In this way the two gages will be adjusted simultaneously to locate the plates as desired.

As indicated in Fig. 1, the gage plates 54 coöperate with the edge of the plate 99 which is adjacent to the guide head 3, while the opposite gage plates coöperate with the edge of the plate 98 which is remote from the guide head 3. In this way the plates are accurately alined with respect to their transverse position in the chase. In addition to alining them in this way, the plates are alined longitudinally by means of the gage plate 23, which may be pressed down at any moment onto the upper face of the form. When pressed down in this way, the plates are shoved up against the plate 23 and this alines the transverse edges of the plates, as will be readily understood. These transverse edges may be alined at any predetermined position by having recourse to the longitudinal scale 83 on the table edge.

In Fig. 1 I have indicated a chase of small dimensions, but large chases may be employed, limited only by the size of the table. In setting up plates, or other parts of large forms such as suggested, the same mode of procedure would be employed, the plates being alined in pairs. As each pair of plates 100 is alined, they would be clamped in position by means of any usual printers' clamps. After alining and fixing one pair of plates, the other plates are successively alined in a transverse row by moving the cross gages along the carriage until the pair of gages nearest to the guide head 3 were brought against the adjacent edge of the second fixed plate, that is, the plate corresponding to the plate 98. The outer gages would then indicate the position of the third plate in the 110 row, and so on.

Where the table is used for setting up forms to use different colors, it is preferable to employ a table corresponding to each color, and when a form has been completely made up, I may then take off proof sheets to ascertain the accuracy of the register of the different colors. In order to enable this to be done, I extend the table at its outer 115 end, and provide a proof cylinder 100 which is mounted on a carriage formed of two oppositely disposed housings 101 sliding on the longitudinal edges of the table. These housings 101 are connected by a cross shaft 120 102, having a hand wheel 103 for rotating it. The shaft 102 is provided with pinions 104 which mesh with the racks 6 in the same manner as the pinions 16, as indicated in Fig. 5. By rotating the wheel 103, the proof 125 130

cylinder may be advanced out over the form which had been set up.

The proof cylinder is simply in the form of a hollow drum, having a platen 105 of 5 rubber and provided with an opening 106 in its face in which clamps 107 and 108 are provided for holding the ends of the proof sheet. The proof sheet is simply wrapped around the wheel of the drum in a well-known manner. The proof cylinder 100 is provided with a cross shaft 109, the ends of 10 which are mounted in eccentric sleeves 110, mounted in bearings 111 in the upper part of the housings. These sleeves, 110, are connected with a bail 112. When the cylinder is not in use, the eccentrics are in the position shown in Fig. 2, with the bail hanging down at the right and resting against the lower part of the housings. If the bail is rotated 15 up through substantially 180° until its arms 113 come against fixed stops 114 on the upper ends of the housings, the cylinder will be depressed and bring its face down to the level of the printing plates. Of course, in the normal or elevated position 20 of the cylinder, it is held sufficiently high to enable it to clear the furniture and all obstructions projecting up from the table, such as the pins 92. Having taken a proof sheet 25 on one table, this proof sheet can then be mounted on the proof cylinder of one of the other tables, and an impression from the form on that table will then show whether the register is perfect.

When it is desired to take a special proof sheet from a form without employing the cylinder 100, I provide for so doing in the manner illustrated in Fig. 3. In order to accomplish this, I push the gages 56 inwardly on their bars 55, or else remove them entirely from their bars, as indicated in Fig. 3. I then secure in place a clamping bar 115, the ends of which are provided with clamps 116, which receive the bars 55 as illustrated. Clamping screws 117 enable these clamps to be adjusted so as to clamp the bars 55 as illustrated in Fig. 4. The clamping bar 115 then extends transversely over the made up form 118, and is provided 40 on the upper face with a clamping batten 119, which may clamp a proof sheet 120 on the upper face of the cross bar as indicated. This device is a quickly operating means but is not so accurate as the proof cylinder, 45 and it is generally used first in order to secure approximate register which can then be perfected so far as possible with the proof cylinder. In introducing the bars 55 into the sockets of the clamps 116, the shoes 50 and 41 may be slid to the proper distance apart on the slide 39 as will be readily understood.

The manner of using the machine for the purpose of locating a number of plates of 55 the same size throughout the form, is illus-

trated in Fig. 8. In order to do this, I slide one of the shoes, as the shoe 41, to the far side of the machine, and I then attach a special clamp 121 to the remaining gages 56. The preferred form of this clamp is shown 70 in Fig. 9. It is formed of two hangers 122, the upper ends of which form sockets 123 which slip over the posts 67 as illustrated in Fig. 9. The lower ends of the hangers 122 are connected integrally by a cross bar 124 75 upon the upper side of which a clamping batten 126 is secured by clamping screws 125. In the clamp 121 I attach a sheet 127 of celluloid or similar transparent material, and upon this celluloid I take an impression 80 of the plate which is to be located at a succession of points throughout the form. The outline of this impression is indicated at 128. Now by means of the longitudinal scale 83 on the table and by means of the transverse scale 13, the clamp 121 can be brought successively into the different positions corresponding to the different plate 85 positions, and while the celluloid sheet 127 is held in one of these positions, the plate 90 to be located at that point is accurately alined through the transparent celluloid, by alining it with the outline 128.

As indicated in Fig. 5, the lower edge of the gage plate 23 is provided with a scale 95 129. This scale is divided in picas or simply into inches, as shown, or it may be a double scale, like the other scales on the machine, that is consisting of an inch scale extending along with a type system scale, such as a pica scale. This scale 129 is particularly useful when the gages 56 are being employed to center two plates by means of the centering gage pointers 71. In order to do this, when one of these stems has been brought to 100 a certain position, the position of the tip of the pointer when slid over against the scale 129 can be observed and then the opposite centering stem 71 can be brought so that its point gives the same reading on the scale. The two centering stems can then be moved 105 out of transverse alinement with each other and can be used to center two plates having center cross marks; in this way avoiding any dependence on the edges of the plates. 110 To secure their proper alinement.

Special attention is called to the alining edge 5 for alining the chases on the table, and also to the fact that the transverse gage 120 guided as it is, always extends at right angles. This edge 5 therefore operates as a base line of measurement. The chases used on the table should be accurately cut rectangles.

When a form has been completely made up it can be removed to the press bed.

The inner end of the gage blade 23 is arranged so that it will clear shoulder 5, and this permits the blade to move clear down onto the surface of the table when desired. 130

On account of the fact that the gage plates can all be raised or lowered, they enable plates to be alined by the edge of the printing face or by the extreme edge of the 5 beveled edge.

It is understood that the embodiment of the invention described above is only one of the many embodiments or forms the invention may take, and I do not wish to be limited in the practice of the invention nor in 10 my claims to the particular embodiment described above.

What I claim and desire to secure by Letters Patent is:—

- 15 1. An imposing machine, comprising a table, means for securing a chase thereupon, a gage overhanging the table mounted to travel longitudinally on said table, a pair of gages mounted to travel transversely of said table, said first gage having an alining edge extending transversely to the table and adapted to lie adjacent the table to aline the edges of the printing plates transversely to said table, said second gages having alining 20 edges extending longitudinally with the table and adapted to aline the edges of the printing plates extending longitudinally with said table.
- 25 2. An imposing machine, comprising in combination, a table, a gage movable longitudinally thereupon and extending transversely to said table, a pair of gages mounted to slide on said first gage and means for locking said pair of gages together to move 30 in unison independently of said first gage.
- 35 3. In an imposing machine, in combination, a table, a carriage, a gage carried thereby overhanging said table, said carriage being adapted to travel longitudinally along 40 said table, means for moving said gage relatively to said carriage, means for moving said carriage longitudinally of said table, a pair of gages mounted to move along said first gage and having parallel gage bars extending substantially parallel with the longitudinal axis of said table, said gage bars 45 having means coöperating to aline a plate lying therebetween.
- 45 4. In an imposing machine, in combination, a table, a gage adapted to travel longitudinally along said table, a pair of gages mounted to slide on said first gage and having parallel gage bars extending substantially parallel with the longitudinal axis of 50 said table, gage plates carried by said last named gages, and means for locking said last named gages together at predetermined distances apart.
- 55 5. In an imposing machine, in combination, a table having an alining head near one edge thereof, adapted to aline a chase supported on said table, a gage traveling longitudinally on said table, a scale extending longitudinally on said table for ascertaining 60 the position of said gage, a pair of

gages traveling on said first gage and having gage plates extending substantially parallel with said alining head.

6. In an imposing machine, in combination, a table, a gage traveling longitudinally thereof, a scale extending longitudinally of said table to determine the position of said gage, adjustable stops attached near the edge of said table for limiting the movement of said carriage, a scale extending 75 along said carriage and transverse to said table, and a pair of gages adapted to move along said first gage and having gage plates coöperating with said second named scale.

7. In an imposing machine, in combination, a table, a gage adapted to travel longitudinally thereof, a scale extending longitudinally along said table, a pair of adjustable stops mounted on said table on opposite sides of said gage for limiting the 85 travel of said gage, and means carried by said stops for adjusting said gage.

8. In an imposing machine, in combination, a table, racks extending longitudinally thereof, a transverse gage extending across said table, pinions moving with said gage and meshing with said racks to advance said gage along said table, graduated wheels at the sides of said table for rotating said pinions, a shaft connecting said pinions, a gage 90 plate carried by said gage, a stop mounted to slide on said table forward of said gage, and having an alining edge adapted to aline with the said gage plate, means carried by said stop for adjusting said gage longitudinally of said table, a scale extending longitudinally with said table and coöperating 95 with the said alining edge of said stop.

9. In an imposing machine, in combination, a table, means for alining a chase on said table with a pair of side rails thereof extending substantially parallel with the longitudinal axis of said table, a gage extending transversely of said table and traveling longitudinally thereof, a pair of gages 100 traveling on said first gage, a scale on said first gage, gage plates carried by said second named gages for alining the edges of printing plates in said chase and substantially parallel with the longitudinal axis of said table and coöperating with said scale.

10. In an imposing machine in combination, a table, means for alining a chase on said table with a pair of side rails thereof extending substantially parallel with the longitudinal axis of said table, a gage extending transversely of said table and traveling longitudinally thereof, a pair of gages traveling along said first gage, a scale on 110 said first gage, gage plates carried by said second named gages for alining the edges of printing plates in said chase and substantially parallel with the longitudinal axis of said table and coöperating with said scale, a connecting rod, and means for ad- 115

- justably securing said connecting rod to said pair of gages.
11. In an imposing machine, in combination, a table adapted to support printing 5 plates, a transverse gage extending across said table and adapted to travel longitudinally thereof, a pair of longitudinal gages sliding on said first gage, said longitudinal gages having horizontal bars extending longitudinally with said table, and gage plates supported by said bars, for alining parallel edges of the printing plates.
12. In an imposing machine, in combination, a table, a transverse gage mounted to 15 travel longitudinally thereof, a pair of longitudinal gages mounted to slide on said first gage and comprising a pair of horizontal bars, longitudinal gage plates supported on said bars and adapted to slide along the 20 same, means for adjustably locking said longitudinal gages together, movable stops mounted on said first named gage for limiting the movement of said second named gages.
13. In an imposing machine, in combination, a table adapted to support printing 25 plates, a transverse gage mounted to travel longitudinally thereof, a gage plate movably mounted on said gage and adapted to descend toward said table, a pair of longitudinal gages mounted to travel on said first named gage, and gage plates carried thereby for alining the longitudinal edges of the plates.
14. In an imposing machine, in combination, a table, a carriage mounted to slide thereon and having a transverse gage overhanging the table, said carriage and gage being mounted to travel longitudinally of 40 said table, a longitudinal gage mounted to slide on said first gage and having a bar extending longitudinally with said table, a gage plate supported on said bar and having an edge extending substantially parallel 45 with the longitudinal axis of said table, and means for adjusting said carriage longitudinally along the table to adjust the position of the gages carried thereby.
15. In an imposing machine, in combination, a table, a carriage movable longitudinally along said table, a movably supported 50 gage plate adapted to descend upon said table, means for normally holding said gage plate elevated above said table, and a movable gage supported on said carriage to cooperate with said first named gage plate in alining a plate on said table.
16. In an imposing machine, in combination, a table, a carriage adapted to travel 55 longitudinally thereof, a pivotally supported gage plate having an alining gage, on said carriage, adapted to descend upon said table, a spring resiliently holding said gage plate elevated, and means for regulating the 60 amount of descent of said gage plate.
17. In an imposing machine, in combination, a table, a carriage adapted to travel longitudinally thereof, a movable gage plate mounted on said carriage adapted to descend toward said table, means tending to 70 raise said gage plate from said table, a member adapted to move when said gage plate descends, and a movable stop in the path of said member, normally preventing the complete descent of said gage plate and adapted to be moved aside to permit a complete descent thereof.
18. In an imposing machine, in combination, a table, a carriage adapted to travel 75 longitudinally thereof, a gage plate supported on said carriage, a gage mounted to slide on said carriage transversely to said table, a gage holder mounted on said last named gage, a gage plate mounted on said gage holder, said gage holder having a post and detachable means mounted on said post to coöperate with said gage plate in alining a printing plate.
19. In an imposing machine, in combination, a table, a carriage mounted to travel 80 longitudinally thereof, gages mounted on said carriage for alining the edges of the printing plates, and means normally held at the end of said table and adapted to advance over said table for applying a proof 85 sheet to the plates mounted on said table, said gages and said means for applying the proof sheet having parallel alining axes.
20. In an imposing machine, in combination, a table adapted to support printing 90 plates, a carriage mounted to travel longitudinally thereof, gages mounted on said carriage coöperating to aline printing plates on said table, a proof cylinder normally disposed at the end of said table and remote 95 from the plates mounted to travel longitudinally of said table and adapted to hold a proof sheet to be applied to the alined plates, the axis of said proof cylinder being parallel with the transverse axis of said 100 table.
21. In an imposing machine, in combination, a table, a rack mounted thereupon, a carriage adapted to travel longitudinally 115 on said table, a pinion in connection with said carriage meshing with said rack to advance said carriage, gages mounted on said carriage and coöperating to aline a printing plate, a proof cylinder having its longitudinal axis at right angles to said rack, said proof cylinder being normally disposed at 120 the end of said table and remote from the position of the plate, a carriage for said cylinder, a pinion in connection with said last named carriage meshing with said rack for advancing said cylinder over the printing plates set up on said table, and means for attaching a proof sheet to said cylinder 125 to be applied to said plates.
22. In an imposing machine, in combina- 130

- tion, a table, a carriage adapted to travel longitudinally thereof, gages mounted on said carriage for alining the printing plates on said table, a proof cylinder, a carriage 5 therefor adapted to travel longitudinally of said table and supporting said cylinder with its axis at right angles to the longitudinal axis of said table, means for attaching a proof sheet to said cylinder, said proof cylinder being normally in an elevated position 13 to permit the same to pass over said printing plates, and means for depressing said proof cylinder so that the surface thereof may touch the printing plates.
- 15 23. In an imposing machine, in combination, a table, a carriage mounted to travel longitudinally thereof, a slide mounted on said carriage, gages mounted to move along said slide, said gages having parallel horizontal bars, and a clamp having sockets received on said bars, said clamp being adapted to support a proof sheet adjacent to the face of said table.
24. In an imposing machine, in combination, a table having an alining edge and having a plurality of sockets in the upper face thereof opposite said alining edge and parallel therewith, a plurality of removable pins adapted to be received in said sockets, 25 a chase mounted on said table, furniture between said pins and said chase for holding said chase in position on said table, a carriage traveling longitudinally along said table, a transverse gage plate mounted on said carriage extending across said table at right angles to said alining edge, and longitudinal gages adapted to move along said carriage transversely to said table, and gage plates carried by said last named gages for 30 alining the edges of printing plates longitudinally with said table.
25. In an imposing machine, in combination, a table adapted to support printing plates, a gage mounted to travel longitudinally thereof, a movable gage plate carried by said gage having an alining edge extending across said table adapted to descend to said table and detachable means for normally holding said gage plate elevated to a 45 point above the printing plates and so that said gage may pass over and out of contact with the plates.
26. In an imposing machine, in combination, a table, a gage mounted to travel longitudinally thereof, a movable gage plate adapted to descend upon said table, a member connected with said gage plate having forks, a spring pressed member received in said forks and detachable therefrom, and a 55 spring normally tending to hold said gage plate elevated above said table.
27. In an imposing machine, in combination, a table, a carriage mounted to travel longitudinally thereof, said carriage comprising a transverse bar, a movable gage 60 plate supported on said carriage and adapted to descend upon said table, an arm in connection with said gage plate and disposed opposite to said transverse bar, a spring between said transverse bar and said arm tending to hold said gage plate elevated above said table, and an adjusting screw carried by said arm and adapted to engage said transverse bar to limit the downward movement of said gage plate. 75
28. In an imposing machine, in combination, a table, a carriage mounted to travel longitudinally thereof, said carriage having a transverse bar extending across said table, a gage plate pivotally supported on said carriage, and adapted to descend toward said table, a spring tending to hold said gage plate elevated, an adjusting screw adapted to move when said gage plate descends and a movable stop in the path of said adjusting screw adapted to control the amount of descent of said gage plate. 80
29. In an imposing machine, in combination a gage, a scale carried thereby, a pair of gages sliding longitudinally with respect to said scale and supported on said first gage, said last named gages having clamping heads, a connecting rod extending through said clamping heads, means for clamping the same in said clamping heads to lock said last named gages together and gage plates carried by said last named gages extending substantially at right angles to said first named gage. 85
30. In an imposing machine, in combination, a table, a carriage overhanging said table and adapted to move along the same, a gage comprising a block sliding on said carriage transversely to said table, said gage having a gage plate with an alining edge extending longitudinally with said table, and means for adjusting said gage plate with respect to said block transversely to said table. 90
31. In an imposing machine, in combination, a table adapted to receive printing plates, a carriage traveling longitudinally thereof, a pair of gages traveling along said carriage and transversely of said table and having parallel alining edges for alining plates between said gages, and stops adjustably mounted on said carriage to limit the movement of said gages. 110
32. In an imposing machine, in combination, a table, a carriage traveling longitudinally thereof, a pair of gages traveling along said carriage and transversely of said table, stops adjustably mounted on said carriage to limit the movement of said gages, and means carried by said stops for adjusting said gages along said carriage. 115
33. In an imposing machine, in combination, a table, a carriage traveling along the same, a pair of gages comprising blocks mounted to travel along said carriage and transversely to said table, said gages having 120

gage plates extending longitudinally with said table, and means for adjusting said gages relatively to said blocks longitudinally of said table.

- 5 34. In an imposing machine, in combination, a table having an alining edge extending longitudinally near one edge of said table, a gage coöperating therewith, and means for guiding said gage in a straight line at 10 right angles to said alining edge to move across said table, and means for simultaneously guiding said gage to move in a straight line parallel with said alining edge to move longitudinally of said table.
- 15 35. In an imposing machine, in combination, a table, a carriage traveling along the same, gages on said carriage, shoes guided on said table, and detachable stops on said shoes for limiting the movement of said car-

riage, said carriage being arranged to pass 20 said shoes when said stops are detached therefrom.

36. An imposing machine comprising in combination, a table having gages for successively setting up printing forms with 25 printing plates, and means movably mounted on said table for transporting a proof sheet over said table and adapted to apply said proof sheet to the successive forms which may be set up on said table. 30

Signed at New York city in the county of New York and State of New York this 15th day of March A. D. 1912.

FRANK C. LEETHEM.
